UNITED STATES PATENT OFFICE.

GEORGE R. WADSWORTH, OF BOSTON, MASSACHUSETTS, ASSIGNOR TO THE PEERLESS MOTOR CAR COMPANY, OF CLEVELAND, OHIO, A CORPORATION OF OHIO.

FASTENING AND LOCKING MEANS FOR THE HOODS OF AUTOMOBILES.

1,269,023.

Specification of Letters Patent. Patented June 11, 1918.

Application filed September 6, 1913. Serial No. 788,376.

To all whom it may concern:

Be it known that I, GEORGE R. WADSWORTH, a citizen of the United States, residing at Boston, in the county of Suffolk 5 and State of Massachusetts, have invented a certain new and useful Improvement in Fastening and Locking Means for the Hoods of Automobiles, of which the following is a full, clear, and exact description.

This invention relates to a fastening and locking means for the hood of an automobile, and has for its chief object to provide a device of the character stated which effectively holds or secures the hood to the frame at a plurality of points, and which can be manipulated from one point to cause the engagement or release of the several coöperating fastening devices and can be 15 locked and unlocked against movement to prevent tampering by an unauthorized person.

The above objects are accomplished by my invention which may be briefly summarized as consisting in certain novel details of construction and combinations and arrangements of parts which will be described in the specification and set forth in the appended claims.

In the drawings, Figure 1 is a sectional view through the hood and chassis of an automobile equipped with my improved hood fastening and locking mechanism; Fig. 2 is an enlarged sectional view showing portions of the chassis, a portion of the hood, and one of the coöperating hood fastening devices, the section being taken substantially along the line 2—2 of Fig. 4; Fig. 3 is a similar view showing the locking mechanism, this section being taken substantially along the line 3—3 of Fig. 4; and Fig. 4 is a side view of the mechanism looking toward the inner side of one half of the hood.

In the drawings, 10 represents the hood which is adapted to be attached to the frame or chassis 11 of an automobile by my improved fastening and locking mechanism. The hood may be of any construction, especially as far as contour is concerned, but it will be formed of the usual number of hinged joints or sections. It will be observed that there are secured to the top flanges of the channels of the chassis, 55 angle member 12, whose upstanding outer

flanges are adapted to be overlapped and engaged by the lower edges of the hood as shown in Figs. 1 and 2. Secured to each side of the chassis and mounted on the horizontal flange of the angle member 12, are 60 a plurality of bearing members 13, in which is supported a rock shaft 14 which extends lengthwise of the chassis frame just within the hood, and adjacent the lower edge of the latter. Each of these shafts has 65 secured to it at intervals a plurality of cam-like hooks 15 which constitute hood fastening devices, and which are adapted to coöperate with others carried by the hood.

Secured to each side of the hood on the inner face thereof, just above the hooks 15 carried by the rock shaft, are brackets 16, each of which is provided with a barrel or socket 16^a, through the base of which extends an eye-bolt or plunger 17 having at its lower end an eye 17^a which is adapted to be engaged by one of the hooks 15. The shank of each of the bolts 17 is surrounded by a coil spring 18 arranged between the 80 base of the socket and a disk or any other suitable shoulder 17^b on the upper end of the bolt, the whole being so disposed that when the hood is in lowered position, and when the rock shaft is turned, the several 85 hooks on the rock shaft will engage in the eyes of the corresponding plungers carried by the hood, and will pull the bolts downwardly, compressing the springs.

Secured to each of the rock shafts 14 at 90 any suitable point is an outstanding arm 19 which extends through an opening 12^a in the vertical flange of the corresponding angle member 12, and through a slot 10^a in the lower edge of the hood, and pivoted to 95 the outer end of this arm is a member 20 which is provided at its upper end with a hook adapted to be grasped by the operator and permitting convenient manipulation of said member. This member 20 carries a 100 lock 21 which may be of any suitable construction, but is preferably cylindrical or circular in contour and is adapted to be projected inwardly when said member 20 is swung upwardly alongside the hood 105 through openings 12^b and 10^b in the vertical flange of member 12 and hood respectively, which openings are in alinement when the hood is in normal position. It may be stated at this point that the vertical 110

flange of each of the angle members 12 is at the point adjacent the lock extended upwardly so that the lock opening 12^b may be formed therein. The inner end of the lock 5 21 is provided with locking tongues 21^a adapted to be moved in or out by a key 21^b.

It will be observed that when the parts are in the position shown in Fig. 3, and when the locking tongues are projected outwardly by the key, the entire mechanism is locked against movement. It will be observed also that at such time, the hood is not only locked against being opened, but it is held to the chassis at a number of points 15 along its length, and it is held firmly at all the points due to the yielding supports for the eye-bolts and to the fact that the springs are under compression when the rock shaft and hooks are in locking position.

20 To release the holding and locking mechanism so as to permit the hood to be opened, the key will be turned so as to withdraw the tongues 21^a of the lock, and thence the hooked member 20 can be swung downwardly. After this member swings through a certain angle, it engages a shoulder 19^b on the arm 19, which as before stated is secured to the rock shaft, and thence further downward movement of the member 20. 25 30 turns the rock shaft so as to cause the hooks to disengage themselves from the eyes of the bolt 17. It will be understood, of course, that the construction above described is duplicated on both sides of the machine or 35 on both sides of the hood.

Having thus described my invention, what I claim is:

1. In combination with the hood and chassis of an automobile, means for fastening the hood to the chassis comprising a set of spaced fastening devices on the hood, a set of correspondingly spaced fastening devices on the chassis adapted to cooperate with the set on the hood, and a movable support carrying the fastening devices of one set and adapted to be operated to cause the latter to be moved into and out of engagement with the fastening devices of the other set. 40 45

50 2. In combination with the hood and chassis of an automobile, a hood fastening means comprising a plurality of fastening devices carried by the hood and spaced lengthwise thereof, each yieldingly sup-

ported, a rock shaft carried by the chassis, 55 having a plurality of fastening devices arranged to engage the fastening devices carried by the hood, whereby when said rock shaft is rotated, the fastening devices carried thereby are moved into engagement 60 with the fastening devices of the hood and maintained under yielding tension.

3. In combination with the hood and chassis of an automobile, a plurality of yieldingly supported fastening devices on 65 the inner side of the hood and spaced lengthwise thereof, a rock shaft supported by the chassis on the inner side of the hood and provided with fastening devices adapted to be moved into and out of engagement with 70 the fastening devices carried by the hood and to place them under tension, and means extending through the hood by which said rock shaft may be rotated.

4. In combination with a hood and 75 chassis of an automobile, means for fastening and locking the hood to the chassis, comprising a plurality of fastening devices on the hood and spaced lengthwise thereof, a plurality of fastening devices on the 80 chassis and adapted to cooperate with those on the hood, a movable member extending longitudinally of the hood for simultaneously actuating the fastening devices of one set, and means connected to said member for locking the same against movement, and for locking the hood against movement 85 in any direction.

5. In combination with the hood and chassis of an automobile, a plurality of fastening devices carried on the inner side of the hood and spaced lengthwise thereof, a rock shaft supported on the chassis and provided with a plurality of fastening devices 90 arranged adjacent to and adapted to cooperate with the fastening devices carried by the hood, said rock shaft being located on the interior of the hood, and being provided with a member projecting through the latter, and means connected to said member for locking the hood to the chassis. 95 100

In testimony whereof, I hereunto affix my signature in the presence of two witnesses.

GEORGE R. WADSWORTH.
